CLAIM

The ornamental design for a foldable solar panel, as shown and described.

DESCRIPTION

FIG. 1 is a front and right perspective view of a foldable solar panel, showing my design.

FIG. 2 is a rear and left perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and bottom perspective view of the foldable solar panel of FIG. 1 in another state; and,

FIG. 10 is a reference view showing a status when the foldable solar panel is folded.

The broken lines shown in the drawings are included for the purpose of illustrating portions of the foldable solar panel that form no part of the claimed design.
